CLAIM

The ornamental design for a plastic box, as shown and described.

DESCRIPTION

FIG. 1 is a front, top perspective view of a first embodiment of a plastic box, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is right-side elevational view thereof;

FIG. 7 is a top plan view thereof;

FIG. 8 is a bottom plan view thereof;

FIG. 9 is a front, top perspective view of the plastic box of FIG. 1 shown in an unfolded configuration;

FIG. 10 is an enlarged view of the area labeled **10** in FIG. 1;

FIG. 11 is a front, top perspective view of a second embodiment of a plastic box, showing my new design;

FIG. 12 is a rear, bottom perspective view thereof;

FIG. 13 is a front elevational view thereof;

FIG. 14 is a rear elevational view thereof;

FIG. 15 is a left-side elevational view thereof;

FIG. 16 is right-side elevational view thereof;

FIG. 17 is a top plan view thereof;

FIG. 18 is a bottom plan view thereof;

FIG. 19 is a front, top perspective view of the plastic box of FIG. 11 shown in an unfolded configuration; and,

FIG. 20 is an enlarged view of the area labeled **20** in FIG. 11.

The dot-dash lines shown in the drawings represent the designation of enlarged views and form no part of the claimed design.
